SHIELDED CABLE

Leslie C. Wolcott, Warren, Ohio, assignor, by
mesne assignments, to General Motors Corpora-
tion, Detroit, Mich., a corporation of Dela-
ware

Application March 25, 1931, Serial No. 525,115

4 Claims. (Cl. 173—264)

This invention relates to high tension cables especially adapted for use in connection with internal combustion engines and, more particularly, to high tension cables having a metallic shield for 5 use on airplane engines.

In order to eliminate interference by the high tension ignition system with the radio receiver of an airplane, it has been necessary to completely shield the entire ignition system by enclosing 10 all units of the ignition system in a well grounded metallic shield. Usually a flexible metallic shield is placed over the ignition cables and this shielding must be grounded at frequent intervals along its length. If this is not done noise in the receiver will develop where the shielding touches the metal of the motor due to the discharge to ground of the induced voltages in the shield. Furthermore, oil, grease, gasoline, and moisture 15 easily penetrate the wire braid ordinarily used for shielding ignition cable and this reduces the efficiency of the shield and shortens the effective life of the insulation on the cable. Also, with the wire braid exposed, it is subject to mechanical damage which tends to reduce the efficiency of 20 the shield and also damages the insulation of the cable.

Another factor that has led to comparatively rapid deterioration of the rubber insulation of the cable has been the corona effect which forms 30 ozone in the air surrounding the insulation and this ozone attacks the rubber and deteriorates its insulating qualities.

It is one of the objects of the invention to provide a cable that will be so constructed as to largely 35 overcome the objections to such cables as heretofore manufactured. It is a further object of the invention to provide a cable that will not require grounding of the shield at frequent intervals and, in the use of which, it will only be necessary to ground the shield at the ends of the cable.

A further object of the invention is to provide a construction that will be practically impervious to salt water, oil, and air so as to avoid the above mentioned deteriorating effects of these on the 45 rubber insulation of the cable.

Other objects of the invention and the features of novelty will be apparent from the following description taken in connection with the accompanying drawing, of which

50 Fig. 1 is an enlarged view of a cable constructed in accordance with my invention, different parts of the cable being broken away to disclose other parts; and

Fig. 2 is a cross-section of a multiple conductor 55 cable embodying my invention.

Referring to the drawing, 10 indicates the usual metallic conductor of the cable which is surrounded by an insulating covering 11 of rubber. Surrounding the rubber 11 is a fabric covering 12 in the form of a braid, such as is commonly used on automotive cables. The braid 12 is given several coats of lacquer, or a suitable varnish, as indicated at 13, to render the braid 12 impervious to water, oil and air. As a further insulation and protection, a tape 14 may be wound over the lacquer coating 13 although, in some instances, the tape 14 may be omitted.

A metallic shield 15 is then applied over the tape 14 or, if the tape 14 is not used, the metallic shield 15 is placed directly over the lacquered braid 12. The shield 15 is in the form of a closely woven braid of flat wires so as to give flexibility. A fabric braid 16 is then woven over the metallic braid 15 and the braid 16 is given several coats of lacquer or a suitable varnish, as indicated at 17.

The different layers of fabric and metal, surrounding the insulation 11, are each tightly applied to the layer underneath so that the coverings will be practically devoid of air and, therefore, there will be no opportunity for the formation of ozone in the coverings.

The braid 16, with the coating 17 thereon, serves as an insulation for the metallic braid 15 and the coating 17 renders the braid 16 impervious to water, oil and air. By thus insulating the metallic shield it is not necessary to ground this shield elsewhere than at the ends of the cable because the braid 16 so insulates the shield that the localized E. M. F.'s that are generated in the shield have no opportunity of forming sparks when the cable touches a metallic part.

Referring to Fig. 2, a plurality of insulated conductors are indicated at 18 and the insulation for these conductors preferably consists of a rubber covering such as is indicated at 11 in Fig. 1, and this rubber covering is surrounded by a lacquer covered braid such as that indicated at 12. This group of insulated conductors 18 is surrounded by a metallic braid 19, similar to the braid 15, and this metallic braid is surrounded by a fabric braid 20 which has a lacquer coating 21.

A cable constructed as described has all of the advantages of prior constructions and has the additional advantage of much longer life and operation at maximum efficiency for a much longer period.

Having thus described my invention, I claim:

1. An ignition cable consisting of a central metallic conductor surrounded by a covering of

rubber insulation, a water-tight and air-tight fabric covering surrounding said rubber insulation, a flexible metallic shield surrounding said fabric covering, and a water-tight and air-tight covering surrounding said shield.

5 2. An ignition cable consisting of a central metallic conductor surrounded by a covering of rubber insulation, a lacquer coated woven braid surrounding said rubber insulation, a flexible metallic shield surrounding said braid, and a lacquer coated woven braid surrounding said shield.

10 3. An ignition cable consisting of a central metallic conductor surrounded by a covering of

rubber insulation, a plurality of layers of insulating fabric surrounding said rubber insulation, a flexible metallic shield surrounding said insulating fabric, and a lacquer coated woven fabric surrounding said shield.

80

4. An ignition cable consisting of a plurality of conductors each of which is surrounded by a covering of rubber insulation having a water-tight and air-tight fabric thereon, said plurality of conductors being enclosed in a flexible metallic shield and said flexible metallic shield being surrounded by a water-tight and air-tight fabric covering.
